UNITED STATES PATENT OFFICE.

REUBEN N. HARRISON, OF PLAINS DISTRICT, VIRGINIA.

MECHANICAL NURSE.

Application filed October 11, 1921. Serial No. 507,012.

To all whom it may concern:

Be it known that I, REUBEN N. HARRISON, a citizen of the United States, residing at Moore Land Hall, Plains District, in the 5 county of Rockingham and State of Virginia, have invented a new and useful Mechanical Nurse, of which the following is a specification.

This invention relates to devices adapted 10 to be placed at the bedside of those temporarily confined as well as invalids and be readily accessible, and in a small way serve as a substitute for an orderly or attendant; the invention being more particularly an 15 invalids' combination desk having a reading-rack, typewriter-stand or table, pigeon hole file cabinet, closets, mirror and the like, constituting parts thereof.

The invention is particularly designed 20 and recommended for those temporarily or chronically confined to bed, incapacitated to the extent of having the use of only one arm or not capable of turning over in bed, the invention being of unmeasurable utility 25 to those not financially able to provide the constant service of an attendant and who would be otherwise in a helpless condition.

The invention consists in the combined 30 arrangement of a cabinet, having compartments adapted for the reception of various and sundry articles, having an interchangeable reading rack, typewriter-stand or table, mirror and the like adapted to be pivoted thereabout and easily brought into position 35 over the bed with only the slightest effort on the part of the person using the same and by the use of which the constant service of an attendant may be made unnecessary.

The invention will first be hereinafter 40 more particularly described with reference to the accompanying drawings which form a part of this specification and then pointed out in the claims at the end of the description.

In this specification and the annexed 45 drawings, the invention is disclosed in the form which it is considered to be the best, but the invention is not limited to such form because it is capable of being embodied in 50 other forms; and it is to be understood that in and by the claims following the description herein it is intended to cover the invention in whatever form it may embody within the scope thereof.

In said drawings:

Fig. 1 is a side elevation of the invention in its application,

Fig. 2 is a side elevation of the reading rack shown in Fig. 1,

Fig. 3 is a similar view showing the reading rack adjusted to a different or closed position,

Fig. 4 is a plan view of the holding device for the reading rack,

Fig. 5 illustrates a plan and side view, 65 respectively, of a modified form of holding device,

Fig. 6 is a front elevation of the rack frame,

Fig. 7 is a front elevation of the main 70 cabinet showing pivoted thereto a file cabinet and a swingable arm for interchangeably carrying or supporting a typewriter, reading rack, mirror and the like devices,

Fig. 8 is a similar top plan view showing 75 the typewriter stand removed from the arm and the pigeon hole file cabinet swung into position extending over the bed,

Fig. 9 is a transverse sectional view of the 80 cabinet taken on substantially line 9—9 of Fig. 7, and

Fig. 10 is a modified form of the invention.

Referring to the drawings, in which the 85 same reference numerals are used to denote corresponding parts throughout the entire views, the numeral 1 designates a cabinet which may be of any desired shape and size, but I preferably provide a cabinet having a top section 4. The cabinet immediately below the top section 4 is provided at its upper portion with a compartment O for the reception of a water pitcher and urinal or the like, and openings in the front side of the cabinet so as to be readily accessible to the invalid. The compartment is closed by a pair of sliding doors 2 and 3, as shown particularly in Figs. 7 and 9. The remaining 90 lower portion of the cabinet 1 may be made to provide a closet P with shelves for books, 100 bed-clothing, or anything of a similar nature. This closet is closed by a door 30 hinged on the rear or back face of cabinet 1, as clearly shown in Figs. 8 and 9.

The top section 4 of the cabinet is provided in its lower portion with a relatively 105 low horizontal extending compartment M, extending substantially the length of the

top, for receiving books, magazines and the like. The upper portion of the top section has fitted therein a pigeon hole compartment 13 suitably divided for the reception of letters, writing material and small articles. This compartment 13 is hinged as indicated at *n* so that it may be swung to a position immediately over the bed by the user, as shown in Fig. 8, whereby it is made easily accessible. On the left hand side of the pigeon hole compartment 13, is another compartment 31 which may receive bottles or other receptacles having considerable height. Obviously, the top section 4 and the compartment 13 thereof may be constructed of any desired shape or size in conformity with the needs of the user; however, I would preferably construct the same in the manner shown in the drawings.

20 I prefer to employ light material in the construction of the entire device as the same is more readily and easily movable.

The top section 4 is slightly larger in size than the body of the cabinet 1 and forms 25 at the front and sides thereof an overhanging ledge X, under which is mounted at the front right hand corner a hinged arm 5 adapted to be swung around to hide the same from view underneath the ledge X of 30 the top 4. The swingable arm 5 is hinged at the points 6 and 7 to the corner post of the cabinet body and has a brace or support 8 attached to the underside thereof, as is best shown in Fig. 7. The outer end of the 35 arm 5 is designed to support a reading rack 11, table 10, or similar devices, all interchangeable at the will of the user of my improved device. From the above construction, it will be readily seen that the arm 5, 40 when swung towards or over the bed upon which the invalid is lying is in a handy position when it is desired to use any of the above devices.

45 The table or stand 10, as shown in Fig. 7, is constructed of a base portion having a peg or center pin at a point preferably near the center of gravity thereof adapted to fit snugly into the hole 9 of the swingable arm 5. A typewriter may be suitably 50 mounted on the table, which may be also used for general purposes including supporting a breakfast or dinner tray over the bed. The arm 5 is also provided with a hole 9^a near its hinged end to receive a pivot 55 pin 47 of the mirror 12, the mirror being so constructed as to be moved in any desired position.

60 Adapted to replace or be substituted for the table is a reading rack 11 comprising a slat frame or rack 14 of a width equal to substantially two-thirds of its length and of a size to accommodate small sized books as well as reasonably large books, magazines and newspapers.

65 The lower edge of the book rack is pro-

vided with a shelf or book rest 19, adapted to prevent a book or other reading matter from slipping off the rack. The reading matter is placed upon the rack 14 and held in position by means of a pair of brackets 15, one at each side of the rack, having inwardly extending slotted or bifurcated arms 16, adapted to fit on upright side strips extending lengthwise at each side of the frame and reciprocable thereon for purposes hereinafter described. A cross arm or bar 17 extends through apertures in ratchet-slides 18, one on each bracket and having a spring pressed latch or pawl adapted for engagement with ratchet-teeth on the under side of the brackets 15, whereby the reading matter is held on the rack when in the position shown in Figs. 1 and 2. The cross rod 17 passes across the open book or reading matter on the shelf 19 and holds it firmly in place against the rack, and the brackets 15 can be moved up and down on the upright side strips at the sides of the rack at will and each independently of the other as may be desired, or to remove the cross rod or bar from the line of print in reading. The rod 17 is shown in dotted lines in Fig. 6 in a diagonal position and thus illustrates how large magazines or newspapers, which have a flexible binding, may be best held in position. The rod 17 is provided at one end with a hook *h* so as to prevent the rod from sliding out of place when the leaves of a book or magazine are being turned from right to the left.

Supporting the rack frame 14, by any suitable means as for example by screw-hooks *a*, at each lower side thereof, is an adjusting frame 20, of substantially an inverted T formation and having its vertical or upright portion slotted or morticed as at *b*, near its upper end with a small nail or pin *c* driven through said slot, as shown in Figs. 2 and 3 of the drawings, to serve as a latch and be engaged by a screw-hook *d* in the back side of the top slat of the rack 14. This construction enables the rack to be unlatched and tilted forward at the top. The latch slot of the mortice is preferably provided of a size sufficient to allow for the upward side thrust necessary to unlatch the rack by slightly lifting either side with one hand. Also the screw-eyes and screw-hooks upon which the rack is mounted, at its base, must have play enough to allow the rack to be lifted enough at either side to unlatch and latch at the top. Located in the bar or upright 20, below the latch slot is a second and larger slot or mortice *e* for the accommodation of a chain 21, adapted to hold the rack in position when unlatched at the top as shown in Fig. 2. Hingedly secured to the upright 20, adjacent the lower end thereof, is a latch piece or ratchet member 22, having ratchet teeth on its underside adapted

for engagement with a pin *f* in a mortice or slot *g* in the lower end of a supporting post or upright 23, hinged at its top to the adjusting frame 20, and to which one end of the chain 21 is attached. The mortice or slot at the center in the base of the supporting post or upright 23, is of size sufficiently large to permit the latch piece or ratchet member to move freely in the mortice when manipulated. The lower end of the upright supporting post 23 is turned down or reduced to form a pin slightly smaller in size than the hole 9 of the swingable arm 5.

In lieu of the construction of the brackets 15 and corresponding parts for holding the reading matter open upon the rack, a pair of brackets 24 as shown in Fig. 5 may be employed. The brackets 24 have inwardly extended bifurcated portions similar to 20 those on the members 15, and also adapted to fit on the upright strips extending lengthwise at each side of the frame and reciprocable thereon. At right angles to the inwardly extending bifurcated portion on 25 the members 24 are a plurality of equidistantly spaced pairs of hooks 25 adapted to receive cross bar 17 and hold the reading matter in place, in a manner similar to the preferred form of the ratchet mechanism 18.

30 In order to manipulate the various elements of this device, particularly by those who are required to constantly lay in bed, use is made of what is termed an anchor stick 32, which is an elongated rod having hooks 33 at its opposite ends. The arm 5 is provided with a corresponding hook or eye 34 in which one of the hooks 33 may be engaged to bring the arm 5 in or out 35 of position over the bed. When the arm 40 is in a position over the bed, as illustrated in Fig. 1, it may be secured in this position by engaging one end of the anchor stick in eye 34 on the arm and the other end in an eye or hook 35 on the cabinet, as clearly 45 illustrated.

When it is desired to use the reading rack, the reduced end of the supporting post 23 is inserted in the hole 9 of the swingable arm 5, and the said arm is swung 50 over the bed of the user and the book or reading matter inserted between the rod 17 and the back of the rack 14. The rod 17 is then moved into engagement with the reading matter and the pawl carried at each 55 end by the end members 18 engages a notch in the under face of its bracket 15 to hold the reading matter in place against the back of the rack. The rack will then be in a substantially perpendicular position as shown 60 in Fig. 3, however, by disengaging the hook from the pin at the top of the device the said top can be tilted forward. To adjust the degree of the tilt the bottom of the post 20 may be moved away from the supporting post 23 so that the teeth on the mem- 65

ber 22 engage the pin in the slot in the member 23. To remove the rack and fold the same the above operation need only be reversed as my reading rack can readily and with extremely great facility be adjusted to suit the line of vision and pleasure of the individual using the same. 70

In Fig. 1, I have shown a swingable arm 26, similar to the arm 5, affixed to the window facing, adjacent the head of the bed, and carrying a mirror 27 pivoted at each side in an inverted U-shaped frame 28, suspended from a slidable member 29 on the arm 26. This mirror can easily be turned and adjusted to any position, and by providing a cord and weight arrangement attached to the opposite side of the window by means of a small pulley, and one end of a cord fastened to the arm, and the cord passed through the pulley with the weight on the other end and the weight will pull the arm 26 away from the bed while I pull it in an opposite direction by means of a small chain attached to the other side of the arm 26. I provide a hook on the desk which engages in the links of the chain to hold the mirror 27 in any desired position and when the chain is released the weight draws the arm 26 carrying the mirror 27 to the opposite side of the window entirely out of the way. This arrangement works perfectly and easily and can be adjusted to any desired position with the tip of one finger and will stay in position until moved by the user. It is extremely useful 80 in connection with the typewriter as each character can be seen as it appears on the paper. 90

Instead of the cabinet 1, about which the various parts are pivotally mounted as 105 shown in Fig. 10, a stand, having a base portion 41 and an adjustable upright body 42 and 43 having a flat top 40, may be used. The adjustable parts comprise a lower body member 42 having a hollow upper end and a spring pressed pawl 44 mounted in bosses thereon adapted to engage notches in an upper or ratchet member 43. A swingable arm 45 similar to the arm 5 is pivoted to the upright body member 43 adjacent the under 110 side of the top member 40. This arm 45 has a hole adapted to receive the supporting pin 46, of a table, reading rack or the like device. At a point near the pivoted end of the arm 45, I provide a second hole adapted 115 to receive the reduced end or pin 47 of a mirror supporting member 38 or the like. The mirror shown in Fig. 10 is mounted similar to that described in Fig. 1, but instead of a swingable arm the supporting member or upright 38 is adapted to turn on the pin 47 in the hole in the arm 45. On one end of the arm 26 carrying the mirror 120 125 130 135 140 145 150 155 160 165 170 175 180 185 190 195 200 205 210 215 220 225 230 235 240 245 250 255 260 265 270 275 280 285 290 295 300 305 310 notched or toothed portion on the upper end of the member 38. If desired the arm 45 and parts supported thereby might be substituted for the arm 5 in the preferred form 5 of the invention. In the last mentioned construction the parts are susceptible of various ranges of adjustment and the device may be found cheaper in construction and more desirable in some cases than that of the preferred form of the invention.

While I have found the foregoing as the most advantageous construction I do not wish to limit myself to the details shown, as obviously various modifications might be 15 made without departing from the spirit of the invention.

Having thus described my invention what I claim as new and desire to secure by Letters Patent is:

- 20 1. A mechanical nurse comprising a cabinet to be positioned adjacent a bed or the like and having a pigeon hole compartment pivotally mounted thereon and normally contained within the confines of the cabinet 25 and capable of being swung outwardly over the bed, the lower portion of the cabinet containing other compartments, a swingable arm hingedly connected to a side portion of the cabinet to also swing over the bed, 30 a reading rack and a table member, and means on said arm to interchangeably support said rack and table member, and means for maintaining said arm in position over the bed.
- 35 2. In a device of the character described, a book and paper support comprising a back frame, brackets connected to and independently vertically slidably along the sides of the frame and having forwardly extending arms, a leaf holding bar loosely supported by said arms and arranged to extend in the general direction of the lines of print, means permitting the rods to be adjusted along said arms toward and away from the frame for

maintaining said bar in contact with the 45 book.

3. In a reading rack of the type described, the combination of a back frame, brackets 50 slidably mounted on the sides of said back frame and having forwardly extending arms, slides mounted on said arms, a leaf holding bar arranged to extend in the general direction of the lines of print and adapted to be loosely attached to said slides, ratchet and pawl mechanism between said 55 slides and arms, permitting adjustment of the bar toward and away from said frame for maintaining said bar in contact with the pages of the book.

4. In a reading rack of the type described, the combination of a post, a member suspended from the upper end of said post and mounted to swing in vertical plane, means for adjusting said member vertically relative to the post, a book rest having its lower end pivotally mounted on the lower end of said member, and means for adjustably securing said book rack in adjusted positions relative to said member.

5. In a reading rack of the type described, 70 a book rest including a back frame against which reading matter may be placed, brackets mounted on the sides of the frame and independently adjustable therealong, a leaf holding bar arranged to extend in the general direction of the lines of print of the reading matter, and loosely extending through said brackets, whereby the rod is maintained in position to hold the book in 75 place on said frame, and a stop means on one end of said rod to engage with the bracket, to prevent the accidental disengagement of the rod from the bracket when the brackets are out of horizontal alignment.

In testimony whereof I have hereunto set 80 my hand.

REUBEN N. HARRISON.
